UNITED STATES PATENT OFFICE.

LUIGI NASI, OF TURIN, ITALY.

PUMP.

SPECIFICATION forming part of Letters Patent No. 341,042, dated May 4, 1886.

Application filed August 25, 1885. Serial No. 175,331. (No model.) Patented in Italy June 25, 1885, XXXVI, 333.

To all whom it may concern:

Be it known that I, LUIGI NASI, a subject of the King of Italy, and a resident of Turin, Italy, have invented certain new and useful 5 Improvements in Pumps; and I do hereby declare that the following is a full, clear, and exact description thereof.

The object of my invention is to produce a pump which is so constructed that the air 10 within the same is automatically replaced when displaced by the constant use of the piston of the same.

Referring to the drawings, Figure 1 is a side sectional view of my improved pump. 15 Fig. 2 is a sectional elevation on line *xx*, Fig. 1. Fig. 3 is a plan view of same. Fig. 4 is an enlarged sectional view showing the automatic device for admitting air in the pump. Fig. 5 shows the application of my principle 20 to great depths.

A is a metallic cylinder, with piston *A'*, piston-rod *A²*, and lever *m*. This cylinder is closed at the top and bottom. This cylinder *A* is joined to receptacle *B* by the tube *C*, as 25 shown, and to the receptacle *B'* by the tube *C*. These tubes *C C* are made of india-rubber.

D are valves. *D'* is the inlet-pipe; *D²*, the outlet-pipe.

The parts can be made of any size and material, and are supported on the bracket *z*, as shown.

By forcing or lifting the arm *m* upward the piston *A'* is raised and the air in cylinder *A* above the piston-head is forced out through 35 the tube *C* into receptacle *B'*, and the air in receptacle *B* is sucked out through tube *C* into the cylinder *A*, below the piston-head. A vacuum is thereby formed in receptacle *B*, which permits the fluid to pass through inlet 40 *D'* and valve *D* into cylinder *A*. When the piston is moved downward, the air in the cylinder *A* below the piston is forced out into the receptacle *B*, on the top of the fluid, and thus forcing it out through the outlet-pipe *D²*. 45 By this downward motion of the piston the receptacle *B'* is emptied of the air and the fluid allowed to enter it as it did receptacle *B*. This operation is kept up as long as the piston is operated; but in course of time the 50 air in *A* will diminish and allow the fluid

to enter it through the tubes *C C* and thereby destroy the use of the pump and its parts. To overcome this difficulty, I use floats *l*, placed within the cylinders *B B'*, connected by arms *h* and *e* to the supports *e²*. The arms are provided with the short arm *g*, which rests upon the top of the weighted end of the valve-arm *d*. They are provided with valves *a*, placed over the openings *c c* in the top of cylinders *B B'*. When the air in the cylinder *A* becomes diminished to such an extent as to allow the fluid to rise in same, it (the said fluid) will touch the float *l*, raise it, and release short arm *g* from valve-arm *d*. This movement allows the valve to immediately 55 open, as there is a vacuum formed in receptacle *B* around the valve. The outside air will then overbalance the weighted end of valve-arm, open the valve, and enter the receptacle *B* through the opening *c c*. When 60 sufficient air has been admitted, the valve will close, the float drop, and hold the valve closed. This action takes place in both receptacles, as they are both provided with this automatic air-admitter. By this construction a sufficient quantity of air is constantly kept up 65 within the pump and the fluid prevented from touching any of the destructive parts, the pump being principally used for fluids containing acids. 70

Fig. 5 shows the cylinder *A* placed at the top of cylinder *B'* below and cylinder *B* midway. It will be seen that the fluid from *B'* is forced into tank *x* and fluid from *B* into tank *y*. By this adjustment I am enabled to raise 75 water to a considerable height. The automatic air-supplier can be used with this arrangement, if necessary.

Having thus described my invention, I desire to claim—

1. In a pump, the automatic air-supplier, consisting of the float *l*, arms *h* and *e*, arm *d*, and valve *a*, in combination with the cylinder *A*, having opening *c*, and the tubes *C C*, substantially as and for the purpose set 80 forth.

2. In a pump, the cylinder *A*, with the piston *A'*, in combination with the tubes *C C*, the receptacles *B B'*, and the automatic air-supplier, consisting of the float *l*, arms *h* and 85

e, arm *d*, and valve *a*, substantially as and for the purpose set forth.

3. In a pump, the cylinder *A*, piston *A'*, tubes *C C*, receptacles *B B'*, valves *D*, outlet-pipe *D'*, inlet-pipe *D''*, float *l*, rods *h* and *e*, arm *d*, valve *a*, opening *c*, and bracket *z*, all arranged substantially as and for the purpose set forth.

In testimony that I claim the foregoing I have hereunto set my hand.

LUIGI NASI.
